[57] CLAIM

The ornamental design for a liquid sprayer, as shown and described.

DESCRIPTION

FIG. 1 is a front elevational view of a liquid sprayer showing my new design;

FIG. 2 is a rear elevational view thereof;

FIG. 3 is a side elevational view thereof, the opposite side being a mirror image of the side shown;

FIG. 4 is a top plan view thereof; and

FIG. 5 is a bottom plan view thereof.

The supply tube has been broken away in FIGS. 1, 2 and 3 to indicate indeterminate length.

FIG. 1.

FIG. 2.

FIG. 3.

FIG. 4.

FIG. 5.
